HAIR TIE.

Application filed July 21, 1923. Serial No. 652,885.

To all whom it may concern.

Be it known that we, EVELYN D. SCHERER and WARREN C. SCHERER, both citizens of the United States, residing, respectively, at 5 Chicago, in the county of Cook and State of Illinois, and Cleveland, in the county of Cuyahoga, in the State of Ohio, have invented certain new and useful Improvements in Hair Ties, of which the following is a specification.

Our invention relates to a hair-tie or clasp, and its object is to provide a device of this kind, which is simple in construction, inexpensive, and which will permit the hanging 15 portion of a woman's hair to be brought together and conveniently tied or clasped, and which further can be shaped to the head and retained in tied or clasped condition and be concealed when dressing the hair in any 20 desired style.

The invention consists in the formation and novel construction of the hair-tie shown in the drawings in which,—

Fig. 1 illustrates the manner in which the 25 device is to be employed.

Fig. 2 is an elevation of the same showing the two connected side members separated to almost their fullest extent.

Fig. 3 is a similar view showing the 30 device partly closed, the retainer projections on each of the connected side members having been passed by the other of said side members.

Fig. 4 is an edge view of the same, with 35 the looped ends of the two side members bent or forced rearwardly to show the manner in which these parts may be curved to conform to the head of the wearer.

Fig. 5 is a view similar to Figs. 1 and 2, 40 showing the device in completely closed condition.

The device is preferably formed of silk or cotton-covered wire, the silk or cotton being of any desired shade so that a hair-tie may 45 be selected that matches or approximately matches the shade of the hair with which it is to be used. This wire is curved midway between its ends, as at 6, to form two opposite inwardly-curved side members 7, 8, each 50 side member being looped upon itself, as at 9, 10, respectively, by recurving or rebending the wire a distance from its opposite ends, as at 11, the loops 9, 10 being comparatively long and narrow and the inner 55 stretches or rebent portions thereof, design-

nated 12, which are formed by the end portions of the wire forming the device, have their extremities twisted around or otherwise secured to the curved side members 7 and 8, as at 13.

It is to be noted that the upper portions of the inwardly-curved side members 7, 8, cross each other and that the rebent portion 12, or inner bounding portion as it may be termed, of one loop passes underneath the 60 two side portions of the other loop, while the rebent or inner bounding portion of said other loop passes above the two side portions of the first-mentioned loop. In this manner the outer portion or stretch of wire 65 of each loop is passed through the other loop.

The inner or rebent portion 12 of each loop has an abrupt inwardly-directed portion 14 formed thereon, which may be 70 termed locking or retaining projections; therefore, each of said inner or rebent portions of the loops may be said to be irregularly formed, by which term we intend to 75 describe a stretch of wire bent or otherwise fashioned to break the direct course or continuity of the same, in contra-distinction to the unbent outer portions of the loops.

The wire from which the device is constructed is yielding, but resilient, so that the parts 80 retain the shape to which they are formed, unless pressure is exerted against any portion, and when such pressure is exerted to cause any portion of the device to move with respect to another or others, or to 85 cause it to conform to the shape of the head by directing the loop portions 9, 10, inwardly, the parts tend to recover their normal position. This is also true of the side members 7 and 8, which are connected 90 at what may be termed the bight 6. The curved portion or bight 6 tends to keep said side members separated. Due to the friction of the wire at the loops, especially since 95 there is normally a slight curvature of the device on its inner side, separation of the side members cannot readily take place except under force, and this is especially true after one of the side members passes the inwardly bent portion or retainer projection 100 14 of the loop on the other side member.

When the parts are in the position shown in Fig. 2, the side members move freely under pressure, but the resistance against closing, gradually increases as each side 105 110

member moves toward the retainer projection 14 of the loop on the other side member, at which point slightly greater pressure is required to move the side member over 5 said retainer projection; this action being best attained by grasping the free ends of the loops 9 and 10, pulling outwardly or away from each other. Under this action the loop 15, which may be referred to as a 10 hair-clasping loop, becomes reduced in size, and after each side member passes over the retainer projection of the loop on the other side member, the parts, due to the inward curvature of the device and due to the fact 15 that each side member extends through the loop of the other side member, are frictionally retained in any position in which they may be placed.

When the free ends of the loops are drawn 20 outwardly to their greatest extent, as shown in Fig. 5, the hair-clasping loop 15 through which the loose hair of the wearer is passed, is reduced to its smallest dimension, and this is sufficient to grasp the loose hair, even 25 though the hair is thin at the point to be grasped. After the hair is passed through the loop 15 and grasped by drawing upon the outer ends of the loops 9, 10, or in other words, by drawing the free ends of 30 the side members outwardly, the loop portions of said side members are forced toward the head and fastened in place by means of hair pins. The device will therefore be retained in closed position and conform as 35 near as possible to the shape of the head. The flowing portion of the hair is therefore tied close to the head and it may then be dressed in any desired form. Under all conditions, however, the dressing of the hair 40 completely hides the hair tie.

Having thus described our invention, what we claim is:

1. A hair tie formed of wire curved upon itself between its ends to provide two side 45 members, said side members having loops at their free ends and that portion of each side member extending through the loop of the other side member forming the outer side of its loop.

50 2. A hair tie formed of wire bent between its ends to form two connected side members, said members being crossed and having loops at their point of crossing, the wire forming the outer side of the loop on

one side member passing through the loop 55 formed on the other member.

3. A hair tie formed of resilient wire concaved on its inner side and curved upon itself midlength to form two curved side members arranged to cross each other, said 60 side members being recurved to form elongated loops, the outer portion of each side member passing through the loop formed on the other side member.

4. A hair tie formed of wire curved upon 65 itself midlength to form two side members, said side members being curved and rebent upon themselves to form elongated loops, the ends of the wires being fastened to said side members between their ends, each of 70 said loops having a retainer projection over which the other side member is adapted to pass.

5. A hair tie formed of wire curved midlength upon itself to form two side members, 75 said side members being curved and crossed and having their ends recurved to form elongated loops with irregular inner bounding portions, the ends of the wire forming said loop being connected to said 80 side members between their ends.

6. A hair tie formed of wire curved upon itself midlength to provide two side members, 85 said side members being curved inwardly to cross each other and the ends of the wires being rebent to form elongated loops through each of which the opposite side member passes, the inner stretch of wire forming each loop having an abrupt inwardly-bent portion serving as a retainer 90 projection over which the side member having the other loop thereon passes.

7. A hair tie formed of wire curved upon itself midlength to form two side members, 95 said side members being curved inwardly to cross each other and having the ends of the wires recurved to form elongated loops and the extremities thereof connected to said side members between their ends, each side member extending through the loop of the opposite side member and being in frictional contact with the two stretches of wires forming said last-mentioned loop.

In testimony whereof, we affix our signatures.

EVELYN D. SCHERER.
WARREN C. SCHERER.
